BIN DISPENSER FOR SMALL CYLINDRICAL ARTICLES

Joseph Fred Knott and Simon Heselov,
Youngstown, Ohio

Application October 29, 1954, Serial No. 32,874

Term of patent 14 years

(Cl. D52—2)

Figure 1 is a front perspective view of a bin dispenser for small cylindrical articles, showing our new design.

Figure 2 is a rear elevation; and

Figure 3 is a side elevation.

We claim:

The ornamental design for a bin dispenser for small cylindrical articles, as shown.
